United States Patent Office.

GEORGE W. BENNETT, OF BROOKLYN, NEW YORK, ASSIGNOR TO HIMSELF,
GEORGE W. PECK, AND CHARLES S. BIRD.

Letters Patent No. 68,158, dated August 27, 1867.

IMPROVEMENT IN PAINT-CANS.

The Schedule referred to in these Letters Patent and making part of the same.

TO ALL WHOM IT MAY CONCERN:

Be it known that I, GEORGE W. BENNETT, of Brooklyn, in Kings county, and State of New York, have invented a new and useful Improvement in Paint-Cans, &c.; and I do hereby declare that the following is a full, clear, and exact description thereof, which will enable others skilled in the art to make and use the same, reference being had to the accompanying drawings, forming part of this specification.

Figure 1 is an under side view of the cover of my improved paint-can.

Figure 2 is a vertical longitudinal section of the same, taken through the line *x x*, fig. 3.

Figure 3 is a top view of the same, the cover being removed.

Similar letters of reference indicate corresponding parts.

My invention has for its object to furnish an improvement in the construction of cans for paint and other purposes, by means of which the can in which the paint or other substance is packed for storage or transportation becomes a vessel from which it may be conveniently used; and it consists in the combination of a cross-bar with the upper end or mouth of the can, and in the combination therewith of a cover having a groove around its under side to receive and fit upon the upper edge of the can, and having a screw attached to its centre which screws into a hole in the central part of the said cross-bar, the whole being constructed and arranged as hereinafter more fully described.

A represents the body of the can, about the construction of which there is nothing new. *B* is a bar, the ends of which are secured to the opposite sides of the can *A*, near its top, as shown in fig. 2. The bar *B* has a vertical hole formed through its central point, having a screw-thread cut in it for the reception of the screw attached to the cover *C*. The cover *C* is made with a groove around its under side, near its edge, of such a size as to fit upon the upper edge of the can *A*. *D* is a screw, attached to the central point of the cover *C* in such a way as to be turned by turning the said cover about upon the mouth of the said can. The screw *D* may be attached to the cover *C* by making its head in the form of a cross-head, which cross-head is let into the body of said cover, as shown in fig. 2; or the screw *D* may be attached to the cover *C* in any other convenient and substantial manner. By this construction, by turning the cover *C* around in one direction upon the top of the can *A*, the screw *D* will be forced into the screw-hole in the bar *B*, drawing the said cover down closely upon the mouth of the said can and tightly closing it; and by turning the cover *C* in the other direction it will be detached from the can. It should be observed that the bar *B* may have a removable handle attached to it for convenience in handling it when the cover has been removed. The bar *B* also serves as a rest to support the paint-brush or other utensil used in connection with the said can when said utensil is not in use.

I claim as new, and desire to secure by Letters Patent—

1. The combination of the cross-bar *B*, having a screw-hole formed through its central part, with the upper part of the can *A*, substantially as herein shown and described and for the purpose set forth.
2. The combination of the cover *C*, having a groove formed in its lower side, near its edge, and having a screw, *D*, attached to its central part, with the cross-bar *B* and can *A*, substantially as herein shown and described and for the purpose set forth.

The above specification of my invention signed by me this 8th day of July, 1867.

GEO. W. BENNETT.
